Primary Examiner — T. Chase Nelson*Assistant Examiner* — Jonathan J Han(74) *Attorney, Agent, or Firm* — Seed IP Law Group LLP(57) **CLAIM**

The ornamental design for a rifle grip, as shown and described.

DESCRIPTION

FIG. 1 is a rear, top, right side isometric view of a rifle grip showing our new design;

FIG. 2 is a front, bottom right side isometric view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a bottom plan view thereof; and,

FIG. 8 is a top plan view thereof.

The broken lines shown in the figures are included for the purpose of illustrating unclaimed features and form no part of the claimed design.

1 Claim, 6 Drawing Sheets(56)
